N - (PSEUDOTHIOURONIUM LOWER ALKYL)-
ENDO-PERHYDRO-4,7-METHANOISOINDOLES
James W. Bolger, Canoga Park, Calif., assignor to Riker
Laboratories, Inc., Northridge, Calif., a corporation of
Delaware
No Drawing. Filed July 27, 1962, Ser. No. 213,031
2 Claims. (Cl. 260—319)

This invention relates to compositions of matter classified in the art of chemistry as substituted isoindoles.

The invention sought to be patented resides in the concept of a chemical compound in which there is attached to the nitrogen atom of an endo-perhydro-4,7-methanoisoindol nucleus a pseudothiouronium lower-alkyl substituent.

As used throughout the specification and in the claims the terms "lower alkyl" and "lower alkylene" embrace straight and branched chain alkyl and alkylene radicals respectively containing 1 to 6 carbon atoms and the term "pseudothiouronium" denotes the monovalent

radical.

The tangible embodiments of this invention possess the inherent general physical characteristics of being, in the form of their acid addition salts, white crystalline solids. Spectral data reveal no unsaturation except as present in the NH portion of pseudothiouronium radical. The aforementioned physical characteristics, taken together with the nature of the starting materials and the mode of synthesis, positively confirm the structure of the compounds sought to be patented.

The tangible embodiments of this invention possess the inherent applied use characteristics of having pharmacological activity as anti-hypertensive agents, local anesthetic agents and as agents for prolonging the effects of pharmacologically active barbituric acid derivatives as determined by recognized and accepted pharmacological test procedures.

The manner and process of making and using the invention will now be generally described so as to enable a person skilled in the art of chemistry to make and use the same as follows:

The starting materials for the compounds of this invention, N-haloalkyl-endo-perhydro-4,7-methanoisoindoles, are prepared according to the method described in my application entitled "N-(Haloalkyl)-Endo-Perhydro-4,7-Methanoisoindoles," Serial No. 213,050 filed July 27, 1962.

The preparation of the tangible embodiments of this invention is illustrated as follows:

where A is lower alkylene and X is a halogen.

2

The reaction depicted hereinabove is carried out by treating the starting material with thiourea in the presence of an inert solvent such as ethanol or propanol at reflux temperature.

5 The tangible embodiments of this invention can, if desired, be converted into their non-toxic pharmaceutically acceptable acid addition or quaternary ammonium salts by conventional procedures. Typical acid addition salts include the hydrochloride, hydrobromide, citrate, maleate, sulfate, nitrate and the like. Typical quaternary ammonium salts are those formed with such alkyl halides as methyl iodide, n-hexyl bromide and the like. Such salts are the full equivalents of the free bases and are included within the scope of this invention.

15 The tangible embodiments of this invention, either as the free base or in the form of a non-toxic pharmaceutically acceptable acid addition or quaternary ammonium salt, may be combined with conventional pharmaceutical diluents and carriers to form such dosage forms as tablets, capsules, solutions, suspensions, suppositories and the like.

20 The best mode contemplated by the inventor for carrying out this invention will now be set forth as follows:

EXAMPLE

25 N-(2'-Pseudothiouronium-Ethyl)-Endo-Perhydro-4,7-Methanoisoindole Chloride Hydrochloride

30 N - (2' - chloroethyl) - endo - perhydro - 4,7 - methanoisoindole hydrochloride (5 g., 0.0212 mole) is mixed with thiourea (1.61 g., 0.0212 mole). Isopropanol (30 ml.) is added and the mixture is refluxed for three hours. Upon cooling the solution white crystals are obtained. Ethylacetate is added to complete crystallization. The crude product obtained in recrystallized from ethanol/ether (anhydrous). Yield 5.6 g. (85%) of white crystals, M.P. 245° C.

35 Analysis.—Calculated for $C_{12}H_{23}N_3Cl_2S$: C, 46.15%; H, 7.42%; Cl, 22.71%. Found: C, 46.07%; H, 7.23%; Cl, 22.62%.

40 The subject matter which the applicant regards as his invention is particularly pointed out and distinctly claimed as follows:

1. A compound of the formula

45 where A is lower alkylene.

2. N - (2' - pseudothiouronium - ethyl) - endo - perhydro-4,7-methanoisoindole.

50 No references cited.
